UNITED STATES PATENT OFFICE.

OSCAR A. ROSS, OF NEW YORK, N. Y.

PACKAGING MEANS.

Application filed October 4, 1923. Serial No. 666,429.

This invention relates to packaging and particularly to the packaging of a plurality of identical unit containers.

The principal object of my invention is to provide a device for the purpose specified which will occupy a comparatively small space for storage before use, be very efficient for accomplishing the object desired, extremely simple and easy to apply and quite inexpensive.

Other objects and advantages will appear as the description of the particular physical embodiment selected to illustrate the invention progresses and the novel features will be pointed out in the appended claims.

In describing the invention in detail, and the particular physical embodiment selected to illustrate the invention, reference will be had to the accompanying drawing wherein like characters of reference designate like parts throughout the several views, and wherein:

Fig. 1 is an end view of a package to which my improvement has been applied; Fig. 2, is a side view of the same package as shown by Fig. 1; Fig. 3, is a top view of the same package as shown by Fig. 1 showing a modified form of locking and tensioning device; Fig. 4, is an end view of the package, as shown by Fig. 1, after being placed in a carton; Fig. 5, is a top view of one of my duplicate packaging means.

Most every body is familiar with the fact that nowdays products of manifold kinds are delivered to the consumers in what might be called standard or unit containers. These are desired by consumers because of the assurance thereby received that the goods are of the quality previously obtained and of the specified weight or volume or quantity.

This form of merchandise obliges the manufacturer and wholesaler to ship goods in a large number of identical containers. These containers are generally of comparatively small size and are often made of so-called, tin. Examples, perfectly familiar, are canned fruits and vegetables, and paint products. In order to ship these goods safely it has heretofore been necessary to enclose a given number of them in a stout box, generally made of wood, in order that the containers could be handled in assembled units of convenient size. The wood adds greatly to the cost of shipping and so to the cost of the goods. Attempts have been made to ship canned goods in cardboard

cartons but it has been found that although the carton is sufficient to protect the goods from injuries from accidental blows, it is not sufficiently rigid to allow the assembled unit to be handled, at least at all roughly.

Applicant's invention contemplates an inexpensive clamping means, whereby the assembled units approximately a parallelopipedon, are tightly clamped together, so as to produce a comparatively rigid structure which may be even roughly handled without falling apart, so that the assembled unit may if desired be placed in a cardboard carton to protect from accidental blows and thus be securely packaged for shipment.

In the drawing, Fig. 1, 5 designates the unit containers, two rows of three each being shown and by reference to Fig. 2 it will be seen that there are four lengthwise of each row so that two dozen unit containers are embodied in the package.

I preferably dispose separators such as corrugated cardboard, between the layers and rows, so that every unit container bears against a separator.

My invention contemplates an angle strip 1 at each of four edges of the package at least. The edges selected may be the four horizontal edges, the side view of which is shown in Fig. 2. In addition I may use four angle strips 9, one at each of the vertical edges, two of which are shown in Fig. 2, and in addition, four angle strips, as 8, at the remaining horizontal edges, two of which are shown in Fig. 2.

The angle strips 1, have inturned ends, as 10, as shown in Fig. 5, but the other angle strips consist merely of the two flange portions one at substantially a right angle to the other.

In each end of each of the angle strips 1, I form orifices, one in one flange, one in the other flange and one in the inturned end. 100 In two of the orifices I fasten in a suitable or appropriate manner as by twisting an end of a length of a flexible connecting body, as a wire, ribbon or cable as 3 and 4, Fig. 5, preferably of metal and the free end of each connecting body is fastened in a corresponding orifice in a like and parallel but reversely placed angle strip, as shown in Fig. 5. I also, likewise, connect a flexible body as 2, at its two ends to each end of an angle strip. 110 The resulting structure is my unit clamping means, and is shown in Fig. 5, and I design-

nate the whole by A. Two of these are required for each package. The other duplicate, one needed I designate as a whole by B.

After the unit containers are arranged as hereinbefore described in two layers of one dozen each with separators between, I place A on the top of the package and B on the bottom place angle strips 8 and 9 in position and join the connecting bodies 2 of A with 10 2 of B; 3 of A with 3 of B; and 4 of A with 4 of B. I may join the connecting bodies or wires in any preferable way as by welding or clamping or by twisting as shown in Fig. 1 or by twisting as shown in Fig. 2 15 or by a locking plate, as 7, having two depending somewhat curved flanges, as shown in Fig. 3.

After the wires as 2, 3 and 4 are connected properly the package will be rigid and may 20 be handled as desired, even if roughly, and may then be enclosed in a comparatively weak cardboard or other suitable container or envelope as 11, Fig. 4, to prevent injury by accidental blows.

25 In many cases the complete clamping means as outlined may be used, but in others the edge strips 8 and 9 will be unnecessary, if the unit containers are not of great weight.

If the containers are round then I may 30 slightly shorten the strips, as 1, so that the wires as 2, 3 and 4, will partially encircle the end containers and so the better hold them from slipping.

35 Although I have particularly described the construction of one physical embodiment of my invention, and explained the operation and principle thereof, nevertheless, I desire to have it understood that the form selected is merely illustrative, but does not exhaust the 40 possible physical embodiments of the idea of means underlying my invention.

What I claim as new and desire to secure by Letters Patent of the United States, is:

1. As a packaging clamp, two angle strips 45 arranged in parallel relation and having in-turned ends and formed with three orifices in each end, four flexible connecting bodies, two engaging at opposite ends in two of the orifices of the corresponding ends of the strips, the other two correspondingly engaged in the orifices at the other ends of the strips and two flexible connecting bodies one engaged at one end in one of the remaining orifices of a strip and the other end in the other 50 remaining orifice of the same strip and the remaining flexible body similarly engaged with the other strip.

2. As a packaging clamp, two longitudinal members adapted to be normally arranged in parallel relation, a pair of flexible members 60 each having one end attached to one end of one of said longitudinal members and each of

the other ends relatively attached to one end of the other longitudinal member, another pair of flexible members each having one end attached to the opposite end of said first named longitudinal member and their other ends relatively attached to the opposite end of said second named longitudinal member, a third pair of flexible members, one end of said last 70 named flexible members having its opposite end secured to the opposite end of one of said longitudinal members and the other flexible member having its opposite ends secured to the opposite ends of the other longitudinal 75 member substantially as described.

3. As a packaging clamp, two angle strips arranged in parallel relation, four flexible connecting bodies, two engaging at opposite ends of the corresponding ends of said strips, 80 the other two correspondingly engaged at the other ends of the strips and two flexible connecting bodies, one end of one engaged at one end of one of the strips and the other end engaged at the other end of the same strip and the remaining flexible member similarly engaged with the other strip substantially as described.

4. As an element of a packaging device, two rigid longitudinal strips arranged parallel 90 one to the other having a length equal to similar edges of opposite faces of the package to be embraced, four flexible connecting bodies, the ends of two of the bodies being connected to one end of one of the strips and the opposite ends to the similar end of the other strip, the other two correspondingly engaged at the other ends of the strips, and two flexible connecting bodies, one end of one engaged at one end of one of the strips and the other end engaged at the other end of the same strip and the remaining flexible body similarly engaged with the other strip.

5. In combination with a package, of an envelope comprising two similar devices each device embracing substantially one-half of the package, each device comprising two rigid longitudinal strips arranged parallel one to the other having a length equal to similar edges of opposite faces of the package, four 110 flexible connecting bodies, the ends of two of the bodies being connected to one end of one of the strips and the opposite ends to the similar ends of the other strip, the other two correspondingly engaged at the opposite ends 115 of the strips, two flexible connecting bodies one end of one engaged at one end of one of the strips and the other end engaged at the other end of the same strip, the remaining flexible body similarly engaged with the other strip, and means for locking the devices together to form a tensioned envelope surrounding the package.

OSCAR A. ROSS.
